(57) **CLAIM**

The ornamental design for a catheter handle, as shown and described.

DESCRIPTION

FIG. 1 is a perspective view of a catheter handle of our new design.

FIG. 2 is a front elevation thereof.

FIG. 3 is a rear elevation thereof.

FIG. 4 is a left side elevation thereof.

FIG. 5 is a right side elevation thereof.

FIG. 6 is a top plan view thereof; and,

FIG. 7 is a bottom plan view thereof.

The broken line showing of parts of the drawings is included for the purpose of illustrating use and environment and forms no part of the claimed design.

1 Claim, 7 Drawing Sheets(56)
